US00D683314S

(12) **United States Design Patent**
Andre et al.

(10) **Patent No.:** **US D683,314 S**
(45) **Date of Patent:** ** *May 28, 2013

(54) **POWER MODULE**

(75) Inventors: **Bartley K. Andre**, Menlo Park, CA (US); **Daniel J. Coster**, San Francisco, CA (US); **Daniele De Iuliis**, San Francisco, CA (US); **Evans Hankey**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Douglas B. Satzger**, Menlo Park, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(*) Notice: This patent is subject to a terminal disclaimer.

(**) Term: **14 Years**

(21) Appl. No.: **29/427,839**

(22) Filed: **Jul. 23, 2012**

Related U.S. Application Data

(63) Continuation of application No. 29/410,267, filed on Jan. 6, 2012, now Pat. No. Des. 664,093, which is a continuation of application No. 29/367,919, filed on Aug. 16, 2010, now Pat. No. Des. 653,213, which is a continuation of application No. 29/354,990, filed on Feb. 1, 2010, now Pat. No. Des. 623,136, which is a continuation of application No. 29/319,237, filed on Jun. 5, 2008, now Pat. No. Des. 611,415.

(57) **CLAIM**

The ornamental design for a power module, as shown and described.

DESCRIPTION

FIG. 1 is a top perspective view of a power module showing our new design;

FIG. 2 is a bottom perspective view thereof;

FIG. 3 is a side view thereof;

FIG. 4 is another side view thereof;

FIG. 5 is another side view thereof;

FIG. 6 is another side view thereof;

FIG. 7 is a bottom plan view thereof; and,

FIG. 8 is a top plan view thereof.

The shade lines in the Figures show contour and not surface ornamentation.

The broken lines in the Figures show portions of the power module which form no part of the claimed design. The dot-dash lines show an unclaimed boundary which forms no part of the claimed design.

1 Claim, 2 Drawing Sheets
